UNITED STATES PATENT OFFICE.

WILLIAM E. WILSON, OF MASON CITY, IOWA, AND HENRY G. LYKKEN, OF MINNEAPOLIS, MINNESOTA.

TUNNEL-KILN FIRE BOX.

Application filed April 5, 1922. Serial No. 549,726.

This invention relates to a new and improved fire box or furnace to be used in conjunction with tunnel kilns for the burning of hollow ware and for other heat treating purposes. Heretofore the heat input into the tunnel kilns has been accomplished by a great many different types of fire boxes, or series of fire boxes arranged side by side or along different points of the tunnel kiln. The heat has been generated by grates or stoker fires projecting into the fire box or boxes, by oil, gas and powdered fuel flames playing into the fire box or furnace, transversely from the side of the furnace or longitudinally along the axis of the furnace, projected in from the end of the furnace. There has also been an attempt to project the heating longitudinally along the top of the ware. Baffle walls have been interposed between the flame and the ware to protect it from excessive heat and the theory has uniformly been to cause the heat to travel upward through the ware or longitudinally through the ware toward the spent gas outlet. Other kilns have been of the muffle type, the combustion and products of combustion being confined in muffles and the heat transfer made by air circulating around the muffles and through the ware.

In the present invention an entirely different theory of heat transfer is relied upon. The ware is burned in a large open chamber and the flame which may be produced by gas, oil, or powdered fuel is projected upwards from a basement under the burning chamber.

Among the objects, therefore, of our invention are to provide new mechanism for heat treating materials, more especially such materials as plastic ware; to provide apparatus which permits materials of the character stated to be heat treated more evenly than is possible with prior constructions; to provide a new method of heat treating plastic wares; and such further objects, advantages, and capabilities as will hereinafter more fully appear.

Our invention further resides in the combination, construction, and arrangement of parts illustrated in the accompanying drawing, and while we have shown therein a preferred embodiment we desire the same to be understood as illustrative only and not as limiting our invention.

In the drawings annexed hereto and forming a part hereof,

Fig. 1 is a sectional plan view substantially along the plane indicated by the line 1-1 Fig. 3.

Fig. 2 is a sectional elevation substantially along the plane indicated by the line 2-2 Fig. 1.

Fig. 3 is a transverse sectional elevation substantially along the plane indicated by the line 3-3 Fig. 1.

Referring more in detail to the drawing, the burning chamber portion A of the kiln is here represented, showing the cars of ware, b, b', and so forth passing in continuous procession through the furnace. The car body has transverse ducts *t* communicating with openings *u* in the car deck upon which the ware is stacked so that the heat may be forced downwardly therethrough and into the said transverse ducts. The ware is usually set with vertical openings *x* through the same. The products of combustion by the action of the flame *e* and by the convection due to heat rise to the roof ceiling *y* of the burning chamber and drop down through the ware, due to the cooling effect of the ware upon the gases. They then pass into the car body and laterally through the openings *d*, *d'* in the baffle walls *c*, *c'*. The relatively cooler gases are reheated and re-circulated as will be obvious.

It will be readily seen that a continuous circulation is thus obtained first upwards in the burning chamber proper A, then along the roof, then downward through the ware *b*, *b'*, and then laterally through the car body and baffle wall back into the burning chamber proper to be recirculated. This circulation will take place automatically due to the descending current in the ware body, caused by the cooling of the gases in the ware, but in this invention it is augmented by the vertical flame *e* acting as an aspirator, tending to cause a pressure upwards in the burning chamber proper and a lateral suction on the air passing through the car body and the openings *d*, *d'*.

It will be noted that a series of flames are contemplated on either side of the moving train of cars. The drawing shows four on either side, but there may be a greater or a lesser number. There are indicated baffle walls, *c* and *c'*, which are interposed be-

tween the flame and the ware to prevent excessive heating of the latter through radiation, the intention being to transfer the heat through the ware primarily by convection, although it is appreciated that the ware will absorb heat from the uniformly heated burning chamber. It is also contemplated that the intensity of the flames along the fire box may be varied, the flames being independently controlled in order to produce any desired heat curve in the burning chamber. The products of combustion may be withdrawn from the burning chamber along the tunnels in either direction, or partially in both directions longitudinally with the ware.

Beneath the floor *w* of the kiln is a chamber or basement *B* in which are located pipes *p* through which the fuel is carried to be discharged through branches *q* into nozzles *a* located in the floor *w*. Each branch *q* may have any suitable control valve *r*. The fuel is projected into the burning or firing chambers *A* where the flames occur as shown at *e*. Either above or below the floor *w* are ducts *f*, *f'* which serve to carry heated gases to the fuel fan or fans during the operation thereof, said heated gases being drawn from the burning chamber through openings *z*. In this way a gradual forward movement of the gases from one end toward the other of the kiln is produced. Suitable damper controlled air inlets *s* may also be provided at intervals in the side walls *m* of the kiln.

It is of course understood that the specific description of structure and method set forth above may be departed from without departing from the spirit of our invention as set forth in this specification and the appended claims.

Having now described our invention, we claim:—

1. A kiln comprising a passage for the movement of ware therethrough, flame chambers at the side of the passage and having floors provided at intervals with flame ports, fuel supply means located beneath said floors and having means for projecting burning fuel upwardly through said ports and into said chambers, whereby the hot products of combustion may pass upwardly to the top of the ware and downwardly therethrough.

2. A kiln comprising a floor, walls and a ceiling, a horizontal partition between said floor and said ceiling and having a port, means beneath said partition for directing upwardly through said port a hot blast, a track supported on said floor, a movable support for material carried by said track and having its upper surface above said partition, the whole structure being adapted to protect said means and the lower portions of said support from the heat in the kiln.

3. A kiln comprising a tunnel for the procession of cars and ware on the cars, flame chambers at the side of the tunnel, said chambers communicating at the lower and upper portions with the upper and lower portions of said tunnel whereby recirculation of hot gases may be effected downwardly in the ware and upwardly in the chambers, said chambers having floors provided with flame ports at intervals, fuel conduits beneath said floors and having fuel projecting means for projecting burning fuel upwardly through said ports and into said chambers. 70 75

4. In a kiln, means for directing a blast upwardly, a compartment having a wall adjacent to said means, means for deflecting said blast downwardly into said compartment, and a duct through said wall having a port opening toward said means and another port opening into said compartment. 80

5. In a kiln having a ceiling, means for directing a blast upwardly toward said ceiling, a support for material to be treated, a wall between said means and said support extending toward the ceiling, a laterally extending passage in said support having upward and sideward openings, and a laterally extending duct in said wall registrable with said sideward opening and having a port 90 95 opening toward said means.

6. In a kiln, means for directing a blast upwardly, a support for materials to be treated, a wall between said means and said support, means for deflecting said blast downwardly toward said support, and a duct through said wall having a port opening toward said means and another port adjacent to said support. 100

7. In a kiln, means for directing a blast upwardly, a support for material to be treated, a wall between said means and said support, means for deflecting said blast downwardly toward said support, a duct through said wall having a port opening toward said means and a second port adjacent to said support, and a passage in said support having a port registrable with said second port and having another port communicating with the top of said support. 105 110 115

8. In a kiln, means for directing a blast upwardly, a support for material to be treated, a wall between said means and said support, means for deflecting said blast downwardly toward said support, a duct through said wall having a port opening toward said means, and a second port adjacent to said support, and means for establishing communication between said second port and the upper surface of said support. 120 125

9. In a kiln having a ceiling, means for directing a blast upwardly toward said ceiling, a compartment and a support therein for material to be treated, a wall of said compartment being disposed between said 130

support and said means, and a duct through said wall having an opening near said means and another opening adjacent to said support, the whole being so adapted that the blast deflected from said ceiling and descending to said support will be drawn through said duct and directed upwardly again by

the aspirating action of the blast issuing from said means.

In witness whereof, we hereunto subscribe our names to this specification.

WM. E. WILSON.
